SECRETARY-TYPE WALLET

Elmer P. Griffith, Canton, Ohio

Application October 21, 1954, Serial No. 32,755

Term of patent 14 years

(Cl. D87—3)

FIG. 1

To all whom it may concern:

Be it known that I, Elmer P. Griffith, a citizen of the United States, residing at Canton, in the county of Stark and State of Ohio, have invented a new, original, and ornamental Design for a Secretary-type Wallet, of which the following is a specification, reference being had to the accompanying drawing, forming a part hereof.

Fig. 1 is a perspective view of a secretary-type wallet, showing my new design, the wallet being shown in open position;

Fig. 2 is a perspective view of the secretary-type wallet in open position showing the opposite side of the wallet to that shown in Fig. 1; and

Fig. 3 is a perspective view of the secretary-type wallet in closed position.

I claim:

The ornamental design for a secretary-type wallet, substantially as shown and described.
